UNITED STATES PATENT OFFICE.

SIGMUND L. GOLDMAN, OF CHICAGO, ILLINOIS.

BOTTLE-CAPPING DEVICE.

Application filed October 17, 1921. Serial No. 506,130.

To all whom it may concern:

Be it known that I, SIGMUND L. GOLDMAN, a citizen of the United States, residing at Chicago, in the county of Cook and State of Illinois, have invented a new and useful Improvement in Bottle-Capping Devices, of which the following is a specification.

My invention relates, more particularly, to devices for applying caps, such as metal caps required to be bent into place, to the mouths of bottles to seal them. My primary object is to provide a novel, simple and inexpensive construction of bottle-capping device which will be highly effective in operation and durable, and more particularly to provide improvements in the head member of the device which carries the cap-engaging cup, to the end that this part of the structure may be simple of construction, economically manufactured and be very rigid and durable, and engage the upright of the device and on which it is supported, in a manner to prevent the objectionable canting of the head on its support.

Referring to the accompanying drawing:

Figure 1 is a perspective view of a capping device embodying my improvements, a portion of the cup-operating lever being broken away. Figure 2 is an enlarged section taken at the line 2 on Fig. 1 and viewed in the direction of the arrow; and Figure 3, a plan view of the structure of Fig. 1.

The particular construction illustrated is formed of a base member represented at 4 comprising a base-plate 5 at which the device is adapted to be supported on a table or any other suitable support, this base-plate being provided with screw-receiving openings 6 at which it may be rigidly secured in place on the support, the base-plate being formed at opposite sides, adjacent its rear end, with upright side-plates 7 preferably formed integral with the base-plate 5 and having inwardly-bent flanges 8 at their rear edges, the lower ends of which reach short of the plate 5 and beneath which an upstanding rib 9 located at the rear edge of the base-plate 5, extends, this rib being preferably integral with the plate 5. The device also comprises an upright represented at 10, shown as formed of a pair of bars 11 the upper portions of which extend in flat-wise-opposed parallel relation to each other with a filler bar 12 interposed therebetween where the bars are relatively light, the parts just described being rigidly secured together,

as by means of the pins represented at 13. If desired, the bars 11 may be made of such thickness as to render the use of the filler bar 12 unnecessary. The lower ends of the bars 11 diverge downwardly, as represented at 14, their lower extremities, represented at 15, extending parallel with each other at which the member 10 is pivotally connected with the plate portions 7 as indicated at 16, the portions 15 extending into the angles formed between the parts 7 and 8. The member 10 is thus pivotally connected with the base portion 4 to permit it to be folded into compact condition for storage; and to releasably hold the member 10 in upright condition on the base 4, a cross-bar 17 is provided which extends through vertically elongated slots 18 in the portions 15 of the bars 11 and, when the parts are in the position shown in Fig. 1, extends into upwardly-opening notches 19, one only of which is shown, in the upper edges of the plate-portions 7. The construction of the base member 4 and the upright 10, together with the locking means of which the bar 17 is a part, is described and claimed in an application filed by me and copending herewith.

The upper bar-like portion of the member 10, preferably contains a vertical series of openings 20 extending therethrough, shown as spaced equidistantly, and which cooperate with means, hereinafter referred to, for holding in vertically adjusted position on the upright 10, the head of the device, represented at 21.

The particular illustrated construction of head 21 is formed of two parallel sleeve-like portions 22 and 23 connected together in spaced relation by a web section 24, the head at its sleeve portion 22 surrounding the upper portion of the upright 10 and being vertically adjustable thereon, the opposite side walls of the sleeve portion 22 containing series of openings 25 adapted to receive a pin 26 which would also extend through the one of the openings 20 in registration therewith. The openings 25 are closely spaced apart, and in combination with the spacing between the openings 20 permit of relatively fine vertical adjustments of the head on the upright 10. The sleeve portion 23 forms a housing for the upwardly-extending stem 27 of the cup 28 provided for engagement with the cap to be secured in position to the mouth of a bottle positioned on the base 4, the stem 27 being vertically

- movable in the sleeve portion 23 and co-operating with an operating lever 29 pivoted at one end, as represented at 30, to the web 24 and connected between its ends with the 5 stem 27, as through the medium of the rivet 31 which extends through slots 32 in opposite sides of the sleeve member 23, it being understood from the foregoing that by the arrangement of the lever as stated the 10 stem 27 and with it the cup 28 may be vertically moved, for the purpose of forcing a cap into applied position on a bottle and thereafter elevating the cup to permit of the removal of the bottle.
- 15 The head shown is formed of two pieces of metal the one bent upon itself to form the sleeve portion 23 and the laterally-extending plate-portions 33 which fit flatwise together. The other piece of metal is bent to 20 form the major portion of the sleeve portion 22, from the open side of which the plate-like portions 34 extend in parallel relation but spaced apart to permit the plates 33 to be telescoped therewith to the position 25 shown in the drawings, in which position these four plates fit flatwise together and are rigidly secured in such position as by the rivets represented at 35. The parts of the structure just described are so proportioned 30 that the outer edges 36 of the plates 33 extend flush with the adjacent ends of the inner surfaces of the opposite side walls of the sleeve 22, and form one of the walls of the sleeve member 22. The rivet 30, as shown, 35 passes through these four-plate-portions 33 and 34 which thus form a very strong and rigid web portion and a very substantial support for the lever 29. It is desirable that means be provided for frictionally holding 40 the lever 29 and the stem 27 in elevated position in order that the cup 28 shall not obstruct the positioning of a bottle on the base portion 4, and as desirable means for accomplishing this I provide spring washers 45 38^a which surround the shank of the rivet 30 at opposite ends thereof and are interposed between the opposite sides of the head 24 and the spaced arms of the lever 29.
- While the head 21 provided, as stated, 50 is of very simple construction and may be economically manufactured, it presents a high degree of rigidity, and the sleeve member 22 while being free to be adjusted vertically on the upright 10, is caused to fit the 55 upright with such a degree of snugness, and is so rigid, that objectionable canting of the head on the upright is prevented. The stem 27 is shown as formed of a pair of flatwise-opposed bars 37 riveted together as indicated at 38 and having their lower ends outwardly turned to form horizontally-extending lugs 39 through the medium of which the cup 28 is secured in position on the stem, the cup being shown as of a shape commonly 60 employed and containing in its upper por-
- tion a cushioning pad 40 which may be of any suitable material, as for example rubber. The cup 28 is secured to the lugs 39 through the medium of the rivets 41, a metal disk 42 being preferably interposed between the 70 lugs 39 and the upper wall of the cup as shown and through which disk the rivets 41 extend. The attachment of the cup 28 to the stem 27, as stated, is of advantage, as a rigid and secure fastening of the cup to the 75 stem, resisting tendency to the twisting or distorting of the cup, which, if it should occur prevents the cap from being properly applied to the bottle, is provided.
- While I have illustrated and described a 80 particular construction constituting an embodiment of my invention, I do not wish to be understood as intending to limit it thereto as the same may be variously modified and altered and the invention otherwise 85 embodied, without departing from the spirit of my invention.
- What I claim as new, and desire to secure by Letters Patent, is:
1. In a bottle-capping device, a head comprising a pair of members of loop form presenting plate-portions, said plate-portions overlapping each other throughout a portion only of the length of said head to present sleeve portions at opposite ends of said head, and means securing said members together at said plate-portions. 90
  2. In a bottle-capping device, a head comprising a pair of members of loop form presenting plate-portions, said plate-portions 100 of one of said members being located between the plate-portions of the other of said members throughout a portion only of the length of said head, to present sleeve portions at opposite ends of said head, and means securing said members together at said plate-portions. 105
  3. In a bottle-capping device, a head comprising a pair of members of loop form presenting plate-portions, said plate-portions 110 of one of said members being located between the plate-portions of the other of said members throughout a portion only of the length of said head, to present sleeve portions at opposite ends of said head, the ends 115 of the inner ones of said plate-portions forming with the walls of the loop portion of the other of said members, a wall of the sleeve portion of the latter, and means securing said members together at said plate-portions. 120
  4. In a bottle-capping device, the combination with an upright, of a head carried thereby formed of a pair of members of loop form presenting plate-portions, said plate-portions overlapping each other throughout a portion only of the length of said head to present sleeve portions at opposite ends of said head, means securing said members together at said plate-portions, one of 125 130

said sleeves surrounding said upright and at which the head is mounted on the upright, a cup-equipped member located, and movable, in the other of said sleeves, and a lever pivoted to said head between said sleeve portions and engaging said cup-equipped member.

5. In a bottle-capping device, a head comprising a pair of sheet metal members bent into loop form with plate-sections extending laterally from said loop-portions, said members overlapping each other at their plate portions, and means securing said members together at said plate-portions, one of said 10 loop portions being adapted to receive a supporting upright.

6. In a bottle-capping device, a head comprising a pair of sheet metal members bent into loop form with plate-sections extending laterally from said loop portions, said plate-portions of one of said members being located between the plate-portions of the other of said members, and means securing 20 said members together at said plate-portions, one of said loop portions being adapted to receive a supporting upright.

7. In a bottle-capping device, a head comprising a pair of sheet metal members bent into loop form with plate-sections extending laterally from said loop portions, said plate-portions of one of said members being located between the plate-portions of the other of said members and forming with the walls of the loop portion of the other 30 of said members a sleeve portion adapted to receive a supporting upright, and means securing said members together at said plate-portions.

8. In a bottle-capping device, the combination of an upright provided with a head having a guide portion, a bar movable in said guide portion and having a cap-engaging cup, a lever for operating said bar, a pin 40 pivotally connecting said lever with said head, and a spring washer cooperating with said lever for frictionally holding the latter in the various positions to which it is movable on its pivot.

9. In a bottle-capping device, the combination of an upright provided with a head having a guide portion, a bar movable in said guide portion and having a cap-engaging cup, a lever for operating said bar, a pin 50

pivotally connecting said lever with said head, and a spring washer surrounding said pin and located between said lever and said head for frictionally holding the lever in the various positions to which it is movable on its pivot.

10. In a bottle-capping device, the combination of an upright, a cap-engaging member movable thereon, a lever pivoted on a part of the device other than said member and through the medium of which said member is operated, and means at the 60 pivotal connection of said lever with said device for holding said lever in the various positions to which it is movable on its pivot.

11. In a bottle-capping device, the combination of an upright, a cap-engaging member movable thereon, a lever pivoted on said device and through the medium of which said member is operated, the pivotal support for said lever comprising a pin engaging said lever and said device, and spring washers surrounding said pin and frictionally engaging the part of said device 70 through which said pin passes for frictionally holding said lever in the various positions to which it is movable on its pivot.

12. In a bottle-capping device, the combination of an upright provided with a head vertically movable thereon, a cap-engaging member on said head, an operating lever fulcrumed on said head, and means at the 85 fulcrum of said lever on said head for holding said lever in elevated position.

13. In a bottle-capping device, the combination of an upright provided with a head vertically movable thereon, a cap-engaging member on said head, an operating lever, a pin on which said lever is fulcrumed on said head, and spring washers surrounding 90 said pin for frictionally holding the lever in the various positions to which it is movable on its pivot.

14. In a bottle-capping device, the combination of an upright, a cap-engaging member movable thereon, a lever pivoted on a part of the device other than said member 100 and through the medium of which said member is operated, and means for frictionally holding said lever in the various positions to which it is movable on its pivot.

SIGMUND L. GOLDMAN.
